United States Patent Office.

JOHN CLIFFORD SHOCH, OF PHILADELPHIA, PENNSYLVANIA.

Design No. 3,600, dated August 3, 1869.

DESIGN FOR A COOK-RANGE.

The Schedule referred to in these Letters Patent and making part of the same.

To all whom it may concern:

Be it known that I, JOHN CLIFFORD SHOCH, of the city and county of Philadelphia, and State of Pennsylvania, have originated a new Design for a Cooking-Range, of which the following is a clear and exact description, reference being had to the accompanying drawings, making part of this specification.

Figure 1. A, fire-front drop-door with oval panel in the centre, ornamented at each end with a leaf, of Elizabethan style; also the centre of oval panel, ornamented with French style leaf.

Figure 4. D, warming-oven door, ornamented at each end of oval panel, also at the top and bottom of oval panel, with leaf, of Elizabethan style; also the centre of oval panel ornamented, as fig. 1, A.

What I claim as my invention, and desire to secure by Letters Patent, is—

The design for a cooking-range herein set forth.
J. CLIFFORD SHOCH.
